Primary Examiner — Kevin K Rudzinski*Assistant Examiner* — Paul D Bohannon(74) *Attorney, Agent, or Firm* — Venable LLP(57) **CLAIM**

The ornamental design for a shirt, as shown and described.

DESCRIPTION

FIG. 1 is a front view of a shirt showing the new design;

FIG. 2 is a right side view thereof;

FIG. 3 is a back side view thereof;

FIG. 4 is a top view thereof;

FIG. 5 is a bottom view thereof; and,

FIG. 6 is a side perspective view thereof.

The broken lines shown in the drawings are for the purpose of illustrating portions of the shirt and form no part of the claimed design. A left side view is omitted because that view is a mirror image to the right side view of the new design. The design includes underarm gussets and a yokeless back of a shirt as shown.
